UNITED STATES PATENT OFFICE.

FERDINAND THIELKE, OF BROOKLYN, NEW YORK.

DESIGN FOR A COVER FOR BOTTLES.

SPECIFICATION forming part of Design No. 25,940, dated August 18, 1896.

Application filed July 21, 1896. Serial No. 600,070. Term of patent 31 years.

To all whom it may concern:

Be it known that I, FERDINAND THIELKE, a citizen of the United States, residing in Brooklyn, county of Kings, and State of New York, have invented and produced a new and original Design for the Tops or Covers of Bottles and Similar Articles, of which the following is a specification, reference being had to the accompanying drawings, in which—

5 Figure 1 is a top plan view of a cover having my design applied thereto. Fig. 2 is a sectional view thereof, the bottle or other receptacle with its hinge being shown in dotted lines.

10 The leading feature of my design consists of a central raised or dome-like portion surrounded by foliage and a series of raised or dome-like portions surrounding the outer side of the cover, said raised portions being separated by leaf-like figures.

15

20

Referring to the drawings, A represents the domed or raised central part, the base of which is surrounded by a wreath of leaf-like figures B, the same being raised, as shown in section in Fig. 2 of the drawings.

C represents a number or series of raised or dome-like portions surrounding the outer side or sides of the article, the spaces intervening between said domes containing leaf-like scrolls D, the latter being raised.

25

30

What I claim is—

The design for a top or cover for bottles and similar articles, substantially as herein shown and described.

FERDINAND THIELKE.
